S. Barnhart

Fan Blower.

№ 13,346.

Patented July 31, 1855.

Fig. 3.

Fig. 1.

UNITED STATES PATENT OFFICE.

SIMON BARNHART, OF CHILLICOTHE, OHIO.

FAN-BLOWER.

Specification of Letters Patent No. 13,346, dated July 31, 1855.

To all whom it may concern:

Be it known that I, SIMON BARNHART, of Chillicothe, in the county of Ross and State of Ohio, have invented a new and useful 5 Improvement in Fan-Blowers of Blacksmiths' Forges, &c.; and I do hereby declare that the following is a full, clear, and exact description of the same, reference being had to the accompanying drawings, forming 10 part of this specification, in which—

Figure 1, is a plan or top view of a fan blower with my improvements, as constructed for a blacksmith's forge. Fig. 2, is a vertical transverse section through the line 15 (x) (x) in Fig. 1, showing an end view of the case and fan. Fig. 3, is a vertical longitudinal section through the line y, y, Fig. 2.

Similar letters of reference indicate corresponding parts in the several figures.

20 My invention relates to an improvement in the construction or form of the blades of the fan, whereby they are rendered capable, as they revolve, of collecting from the outside of the case and forcing and drawing 25 into the case simultaneously with the expulsion of the air already therein, an additional quantity of air besides that which naturally flows in to supply the place of that expelled, and thus facilitate and increase the action of 30 the blower or increase the pressure in the pipe which conducts the air to the fire—to a very great extent, without the necessity of employing additional power, or increasing the size of the fan.

35 The nature of said improvement consists in making each of the blades with a flange or lip on one of its sides, said flange or lip being straight or at right angles with the blade from the tip to the center of the same 40 and therefrom is bent down and made to extend obliquely outward in such a manner that a small spiral wing is formed, on each blade, which extends outside the case through the inlet air passage of the same 45 and, as the fan revolves, collects and forces an additional quantity of air into the case.

To enable others skilled in the art to make and use my invention I will proceed to describe its construction and operation mi- 50 nutely.

A, in the accompanying drawing repre-

sents the fan case constructed in the usual manner with an inlet B, and discharge C.

D, is the taper tube through which the air is forced in its passage to the fire. 55

E, is the shaft of the fan resting and turning in bearings a, a, attached to the sides of the case A.

F, F, F, F, are the blades set as usual tangentially on the shaft E, and curved in a reverse direction to that in which they revolve so that they shall more readily throw off or expel the air or not lift and carry it around in a circle. b, c, represents the flange or lip provided on each of the blades for 65 catching and forcing an additional quantity of air into the fan case as the fan revolves, b, indicating the portion which stands at right angles to the blade and c, the portion which is bent down and made to extend obliquely 70 outward through the inlet air passage B, and has a slight spiral twist given to it as shown in the drawing; the portion c, forms the small spiral wing which collects air from the outside of the case and forces it 75 into the same.

Operation: The fan is caused to revolve in the direction indicated by the arrows 1, by means of a treadle through a band leading from a large fly wheel to a pulley on the fan 80 shaft and the small oblique spiral wings consequently caused to come in contact with the atmosphere, indicated by the arrows 2, outside the case and owing to their shape collect and force it into the case as indicated by the 85 arrows 3, and thus simultaneously with the expulsion of the air already in the case an additional quantity beside that which naturally flows into the case is supplied and the pressure in the pipe leading to the fire con- 90sequently increased to a considerable degree.

What I claim as my invention and desire to secure by Letters Patent is—

Providing each of the blades of the fan with a lip or flange b, c, substantially as and 95 for the purposes herein set forth.
